CHANGEABLE SIGN DEVICE

Lester C. Shaw, Alameda, Calif., assignor of
one-half to Cyril M. McKee, Oakland, Calif.

Application June 15, 1933, Serial No. 675,895

2 Claims. (Cl. 40—143)

The invention relates to changeable display signs, and more particularly to a device for providing sign characters of such signs.

An object of the invention is to selectively provide the different sign characters of a series thereof by appropriate assemblies of a certain few elements which themselves define character portions.

Another object is to provide any one of the series of sign characters at a given position in the sign by the use of fewer character-forming elements than there are characters in said series whereby to minimize the number of elements required for providing the characters of the series.

A further object is to provide for a simple and independent mounting of each of the elements in a character-forming assembly thereof and at the desired position in the sign.

20 A more specific object is to provide for the optional definition of any one of the numerals zero to nine inclusive by the use of a set of as few as five of the aforesaid character-forming elements.

The invention possesses other objects and features of advantage, some of which, with the foregoing, will be set forth or be apparent in the following description of a typical embodiment thereof, and in the accompanying drawings, in which,

30 Figure 1 is a face view of a sign embodying certain features of the present invention.

Figure 2 is an enlarged view of the reverse face of an element of the sign, said element shown as detached from the sign.

35 Figure 3 is an enlarged face view of a series of blanks for providing changeable elements of the sign, said blanks shown mutually related in an arrangement for their economical stamping from sheet material.

Figure 4 is an enlarged and fragmentary face view of a portion of a backing plate of the sign.

Figure 5 discloses the numeral zero provided at the backing plate portion shown in Figure 4.

Figure 6 is a section at 6—6 in Figure 5, with thicknesses exaggerated.

45 Figure 7 discloses numeral-forming elements of the sign as assembled for defining the numerals zero to nine inclusive for mounting on the backing plate of the sign.

Figure 8 discloses opposite face views of one numeral-forming element of a set of such elements for use in forming the numerals of Figure 7.

The features of the present invention are particularly designed for application in display signs whereby variable information may be presented

to the public in a prominent manner. As particularly illustrated in Figure 1, said features are incorporated with a sign 11 on which the price of motor gasoline is to be displayed, the various sign characters being at and on a backing plate 12 mounted in a suitable supporting frame 13. Certain unvarying information of the sign may be permanently printed or inscribed directly on the backing plate 12; in the present instance "gasoline" and "1st grade" are so provided.

A removable sign member 14 has painted on one face thereof the cent symbol, as is shown in Figure 1, while the other face of the member 14 bears the half-cent symbol, as is shown in Figure 2. As particularly disclosed, the member 14 is hexagonal and is provided at opposite sides thereof with integral tongues 17 for simultaneous insertion in spaced slits 18 of the plate 12 for securing the member in place beneath the numeral characters 19 of the sign. Members 21 and 22 are mounted at opposite sides of the member 14, each said member comprising a plate having supplementary information inscribed thereon and provided with tongues 23 at its opposite ends for insertion in slits 24 of the plate 12 for removably mounting the members 21 and 22 in place.

It will now be noted that the numeral sign characters 19 may each vary from zero to nine as the number to be presented varies, and must therefore be changeable. As shown, two characters 19 are provided on the sign whereby any two-digit number may be presented by different combinations of numeral characters of two sets thereof. For reasons which will hereinafter be brought out or be apparent, it is preferred to provide the various numerals of each set thereof by suitably assembling on the backing plate 12 character-forming elements which may be variously associated to provide all of the ten numerals of a set thereof.

By particular reference to Figures 3 and 7, it will be seen that the various numerals zero to nine inclusive are provided by suitably assembling two or more elements 31, 32, 33, 34, 35, 36, and 37. For defining the different numerals, the appropriate character-forming elements aforesaid are arranged for a mutual overlapping thereof whereby the combined elements generally define the outlines of the different characters provided therewith.

It will now be noted that the elements 31 and 32 are of like size, and are U-shaped within the outline of a square whereby the outer side and base lines thereof have the same length, said length conveniently designated in Figure 3 by the

letter "a". The side and base portions of the elements 31 and 32 are of equal widths "b" whereby these elements may be variously combined for defining the numeral characters zero, two, three, five, six, eight, and nine in the manner indicated in Figure 7. With the elements 31 and 32 shaped as described, it will be seen that the aforesaid characters are rectangular, and that, algebraically expressed, each said character has an outside width of a and a length of $2a-b$. In the present instance, though not necessarily, the measurement b is one-third of the measurement a , whereby the width of each said character may be algebraically expressed as $3b$ and the length of the character as $5b$.

The elements 33 and 34 are of like rectangular outline, and essentially have the width b and length $2a-b$; in the specifically disclosed embodiments thereof, these elements have a length of $5b$. The element 35 has a width of b and length a , the latter equaling $3b$ in the present instance. Each of the elements 36 and 37 has a width of b and a length of about four-thirds b ; it is noted that the elements 36 and 37 provide decorative terminal portions of certain of the numerals which are defined by means of various assemblies of the five elements 31 to 35 inclusive, the latter elements essentially defining said numerals.

Figure 7 is seen to disclose in detail the specific assemblies of the different elements 31 to 37 of a set thereof for defining the various numerals zero to nine inclusive, it being noted that the outlines of the element combinations are themselves arranged to define the numerals. For the latter purpose, the exposed faces of the elements are finished uniformly and alike as to color, and the color thereof is arranged to contrast with the color of the backing plate 12; it is generally preferable that the background color of the backing plate be relatively dark while the character elements are relatively light colored whereby the lines of overlap of the elements with each other and with the backing plate may be inconspicuous.

For further completing the definition of the numeral 3, one face of the element 31 may have areas 41 and 42 thereof finished as is the exposed face of the backing plate 12. The area 41, it is noted, extends across the free end of the lowermost arm of the element 31 which defines the upper part of the numeral, and for a distance less than the width b of said arm. The area 42 generally defines an isosceles triangle having its base at the base line of the element 31 and its apex in the central line of the element arm on which the area 41 is defined. In this manner, the areas 41 and 42 are arranged to appear as part of the background for the characters, and the definition of the numeral three is enhanced.

It is noted that the assembly for the numeral eight is the same as for the numeral three except that the element 33 is utilized instead of the elements 36 and 37. The element 33 extends across the free ends of the elements 31 and 32 to conceal the area 41 of the former, and is preferably provided on the exposed face thereof with an area 43 having the form and finish of the area 42 of the element 31; the triangular area 43 is provided at the middle of a side edge of the element 31 with its base lying along said edge whereby the defined numeral 8 is symmetrical with respect to its upright axis.

It will now be noted that the character-defining elements 31 to 37 inclusive are each provided with integral tongues 44 extending therefrom for

disposal in slits 45 provided in the backing plate 12 whereby to mount the elements on the plate in any one of the disclosed character-defining assemblies thereof. The tongues 44 of the elements 31 and 32 extend in the central axial lines of the arm portions of these U-shaped elements, while the tongues 44 of the elements 33 to 37 inclusive extend in the central longitudinal axes of the latter elements. The various tongues 44 may be finished or colored as the background provided by the plate 12.

It is noted that certain of the slits 45 which are utilized in effecting assemblies of the elements for providing the various numerals define the boundaries of the rectangular plate area within which all of the numerals but four and seven completely fit. Certain of the slits 45 are defined without and within the aforesaid plate area for receiving tongues 44 of the obliquely placed element 33 as applied in defining the numerals four and seven, and other slits 45 are provided within said plate area for receiving those tongues 44 of the elements which fall within said area as said elements are applied in the number assemblies.

The various tongues 44 preferably extend rigidly from the elements whereby said elements must be flexed or sprung into their mounted places on the backing plate 12. Accordingly, the elements 31 to 37 inclusive are arranged to be formed of a resilient sheet material. As particularly illustrated in Figure 3, the sign members 14 and 21 and 22 and a set of the elements 31 to 37 are shown in an arrangement for the economical stamping thereof from a sheet of spring steel or other suitable material, it now being noted that the members 14 and 21 and 22 are also arranged to be sprung into their places on the backing plate 12 whereby their securing tongues need not be bent at the bases thereof.

Preferably, and as brought out in Figure 6, the material at the appropriate side of each tongue-receiving slit of the backing plate 12 is raised or offset forwardly from the plate to receive the appropriate tongue, or tongues, therebeneath. In this manner, the attached members and elements may lie flat after being sprung into their appointed places. By providing the aforementioned dark finish on the plate 12, it will be understood that the slits 45 not covered by character-forming elements will be generally unnoticeable to a person looking at the sign.

As is particularly brought out in Figures 6 and 7, the numeral zero is defined by mutually aligning the side portions of the elements 31 and 32, with the elements reversely related and mutually overlapped for the distance b . Since the side portions of the element 31 overlie the side portions of the element 32, the latter element is accordingly provided with slits 46 formed similarly to the slits 45 and receiving tongues 44 of the element 31 thereat whereby the zero assembly of the elements 31 and 32 may be held in its place on the backing plate 12 as a unit.

While I have hereinbefore described the provision and use of a set of character-forming elements for providing a series of numerals, it will be understood that certain principles and devices herein described are applicable to the provision of letters or other characters on a sign. Furthermore, the actual design of the elements and defined characters may vary somewhat, both through altering the shapes and relative dispositions of the elements. Thus, in the present in-

stance, the corners of the elements 31 to 37 inclusive may be left pointed or be cut off angularly instead of being rounded as is particularly disclosed, it being generally necessary, however, that 5 all the corners of all the elements be shaped alike whereby the elements may best cooperate in their different assemblies.

From the foregoing description taken in connection with the accompanying drawings, the advantages of the construction and method of operation will be readily understood by those skilled in the art to which the invention appertains, and while I have described the principle of operation, together with the device which I now consider to 10 be the best embodiment thereof, I desire to have it understood that the device shown is merely illustrative, and that such changes may be made, when desired, as fall within the scope of the appended claims.

Having thus described my invention, I claim as new and desire to secure by Letters Patent of the United States the following:

1. In a changeable sign, a backing plate provided with tongue-receiving slits, means for de-

fining a changeable sign character on said plate and comprising a plurality of elements for mutual and variable overlapping to cooperatively define any one of a series of sign characters, and tongues extending laterally and oppositely from said elements for engagement in appropriate said slits of the plate whereby to secure an assembly of the elements in character-defining relation, said elements formed of resilient sheet material for springing into place between slits receiving the 10 tongues thereof.

2. In a changeable sign, a backing plate provided with tongue-receiving slits, means for defining a changeable sign character on said plate and comprising a plurality of elements for mutual and variable overlapping to cooperatively define any one of a series of sign characters, and tongues extending laterally and oppositely from said elements for engagement in appropriate said slits of the plate whereby to secure an assembly of the 15 elements on the plate in character-defining relation.

LESTER C. SHAW.
